UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A BASKET-GRADE.

SPECIFICATION forming part of Design No. 36,053, dated September 9, 1902.

Application filed July 29, 1902. Serial No. 117,573. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Basket-Grates, of which the following is a full, clear, and exact description, reference being had to the accompanying drawing, forming part hereof, in which the invention is illustrated in perspective view.

The leading features of my design consist of a grille-like front portion having its top edge terminating in scrollwork at the tops of the corner-posts, an arched middle top portion having a central depending shell-like formation, and above the shell an overhanging scroll-like ledge. The top bar of the grille from a point near to the corner-posts to the central arch is of concave curvilinear form. Extending across the front of the grille from each side to the center of the edge of the shell is a garland, the garlands having at their outer ends ribbon-like streamers and connected at their inner ends by a common streamer.

The back piece of the grate is solid and is of the same general outline along its top edge as the grille-front, excepting that at its center it has a straight molding, upon which is formed a casket or shield-like portion bearing a head 30 in relief. Extending upwardly on the back portion from the lower central portion thereof divergently in relief are sprays of foliage and flowers intermingled one with the other.

The front and back pieces are connected 35 with each other by side pieces.

Below the grille-front is a frame extending for the width of the grate.

I claim—

The ornamental design for a basket-grate 40 as herein shown and described.

In testimony whereof I have hereunto set my hand in the presence of two subscribing witnesses.

THOMAS M. DUDGEON.
